[57] CLAIM

The ornamental design for the wheelbarrow handles, as shown and described.

DESCRIPTION

FIG. 1 is a front elevational reduced view of the wheelbarrow handles showing my new design, the broken line showing of the wheelbarrow being for illustrative purposes only and forming no part of the claimed design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

FIG. 1

FIG. 2

FIG. 3

FIG. 4

FIG. 5

FIG. 6
